UNITED STATES PATENT OFFICE

DAVID LONDON, OF BALTIMORE, MARYLAND

GARMENT BAG

Application filed August 5, 1930. Serial No. 473,151.

The present invention has in view the provision of a foldable wardrobe bag which is so constructed that the garments may be readily placed in or removed therefrom and when the bag is closed provides a substantially sealed container for the garments, thus preventing the entrance of moths and dust.

The invention contemplates a wardrobe bag with rectilinear side and end walls, each of the walls being constructed of flexible material which are joined together at their edges by a binding and so arranged that one of the sides may be opened its entire width in order that one or more garments may be readily inserted or removed therefrom and with a continuous interlocking fastening means arranged about the three sides of the opening and the closure providing an effective means for sealing the container.

Another object in view is the provision of a wardrobe bag with a rectangular opening on one side so that the garments may be inserted therein endwise and any one of the garments therein may be removed without disturbing the rest of the garments.

With these and other objects in view the invention resides in the novel features of construction and arrangement of parts which will be more fully described and claimed hereinafter. The invention is illustrated in the accompanying drawings in which

Fig. 1 is a perspective view of the garment bag in closed condition;

Fig. 2 is a cross sectional view on line 2/2 of Fig. 1, taken in the direction of the arrows;

Fig. 3 is a fragmentary cross sectional view on line 3/3 of Fig. 2 showing the bag open and the closure fastened to the rear face of the bag;

Fig. 4 is an enlarged fragmentary cross sectional view on line 4/4 of Fig. 1, and

Fig. 5 is an enlarged fragmentary cross sectional view on line 5/5 of Fig. 1.

In the drawings illustrating one embodiment of the invention, a clothing bag 10 is shown which may be constructed of any suitable flexible material, such as cretonne or the like, and which consists of the rectangular side walls 11 and 12, end walls 13 and 14, and top and bottom walls 15 and 16. Each of

these walls is preferably made of one piece of material and adjacent walls are secured together by a binding 18 which overlaps their meeting edges, and with a row of stitching extending through the binding and the material.

The end wall 13 is provided with a rectangular flap or closure 19 which is secured to the rear wall 12 of the bag along the vertical side edge 20 and is arranged to be folded around the said side edge and to be secured to the rear wall 12 by a snap fastener 21 to hold the said flap or closure open, thus producing a rectangular opening in the wall 13 extending the full width of the bag and substantially the full length of the bag. The flap or closure 19 is arranged to be closed by means of a continuous interlocking fastening device 22 which extends continuously along the top, side and bottom free edges of the closure and along the corresponding edges of the opening in the wall 13. This fastening device may be of any preferred type or construction and, as shown in the drawings, is of the slide type consisting of two rows of interlocking elements 23 and 24 carried by strips of webbing 25 and 26 respectively and with a slide 27 operating to engage and disengage the rows of interlocking elements. The webbing 25 carrying the row of interlocking elements 23 is secured to the binding along the edge 28 of the top wall 15 and along the vertical edge 29 of the side wall 11 and across the wall 13 at 30. The webbing strip 26 carrying the other row of interlocking elements 24 is secured to the binding along the top edge 31, vertical side edge 32 and bottom edge 33 of the flap or closure 19.

When in closed engagement the upper portion of the fastening device 22 lies in the plane of the top wall 15 and the vertical portion lies in the plane of the wall 11 and both of these project beyond the normal face of the wall 13.

The bag is provided with any suitable supporting frame 34 extending about the edges of the top wall 15 within the bag and with a supporting hook 35 projecting through a central opening in the top adapted to be hung on a rod for suspending the bag in a closet. Within the bag the hook 35 terminates in two

oppositely extending members which connect at their ends to the sides of the frame, the said members being provided with a series of U-shaped bends on which garment 5 hangers may be hung.

The closure 19 may be swung to open position and secured by the snap fasteners 21 to the wall 12, so that a full, unobstructed opening is provided to give access to the interior 10 of the device and a clear vision of the interior, so as to insure the proper position of the garments in an unwrinkled condition therein.

One end of the frame 34 adjacent the opening in the wall 13 is located in a pocket 15 formed by the top wall 15 and a strip of material 36 secured at its ends to the binding joining the top wall 15 and the side walls 11 and 12 and connected to the binding along the edge 28. This pocket prevents the hanger 20 from projecting out through the opening in the wall 13 when the closure 19 is opened.

Having described my invention, I now claim:

1. A foldable garment bag constructed of 25 flexible material and having side and end walls secured together at their edges to form a rectangular shaped bag in cross section, one of said side walls having an opening extending the full width of the said side and from 30 the top edge of the bag substantially the full length of the side; a closure for said opening secured to the bag along one vertical edge, the free edges of said closure and the corresponding edges of said opening being provided 35 with complementary fastening devices to hold the closure in closed relation, the said fastening devices when in closed position projecting beyond the normal face of the said side wall, the upper portion of said fastening 40 devices lying in the plane of the top wall and the vertical portion of said fastening device lying in a plane at right angles to the side wall containing the said opening and a rectangular shaped supporting structure located in the top of the bag on which the said 45 bag is hung.

2. A foldable garment bag constructed of 50 flexible material and having side and end walls secured together at their edges to form a bag of rectangular shape in cross section, one of the sides of said bag having a rectangular shaped opening extending the full width of the said side and substantially the 55 full length of the bag, a closure for said opening secured along one vertical edge of the bag, fastening means secured along three edges of said closure and cooperating fastening means secured along the corresponding 60 edges of the opening for securing the closure in closed position, a rectangular shaped supporting structure located in the top of the bag on which the said bag is hung and a narrow strip of material secured along three of 65 its edges to the underside of the top wall of

the bag and adjacent the opening in the said side wall forming a pocket with the top wall in which the one end of the rectangular supporting structure is positioned.
